(57) **CLAIM**

The ornamental design for a space-center toy, as shown.

DESCRIPTION

FIG. 1 is a side view of an entrance-exit panel of the space-center toy showing my new design;

FIG. 2 is a side view of a window panel of the space-center toy showing my new design;

FIG. 3 is a top view of the space-center toy;

FIG. 4 is a bottom view of the space-center toy; and,

FIG. 5 is a perspective view of the space-center toy.
The numbers and letters shown in some of the Figures are unclaimed portion of my new design.
